[57] ABSTRACT

In a yarn spinning machine apparatus for mounting the bearing assembly of the spinning turbine. The apparatus comprising a bushing member secured to the machine frame or frame support and a resiliently yieldable member. The bushing envelopes the bearing assembly and is spaced therefrom to provide a radial clearance. The yieldable member is interposed between the bushing and the surface of the assembly and is secured to at least a portion of the bushing and to only a portion of the surface of the bearing assembly.

APPARATUS FOR MOUNTING A SPINNING TURBINE

BACKGROUND OF INVENTION

The present invention relates to yarn spinning machines and in particular to apparatus for mounting spinning turbines, spinnerettes, and the like.

Synthetic yarns are formed in spinning turbine which are supported on a rotatable shaft, driven by a source of rotary power. The shaft is journaled in a bearing assembly which is rigidly secured within a mounting hole or fixture in a frame or other machine supporting member. The shaft is driven at high speed to spin the turbine and thus centrifugally form or process the yarn. The economics of spinning turbine operation (i.e. maximum yarn output) depends primarily on the rotary speed of the turbine; the higher the rotary speed, the more yarn is produced per unit time.

The rotary speed of the spinning turbine, however, is substantially limited by the known bearing arrangements to approximately 30,000 rpm. The cause of such a limitation is to be found in the rigid mounting of the bearing assembly in the machine frame. As a consequence, vibrations generated during operation of the spinning turbine are transmitted to the bearing of the turbine shaft subjecting it to undue strain and as a result a rotary speed beyond the stated 30,000 rpm. cannot be successfully obtained nor can satisfactory yarn be produced at that speed.

It is an object of the invention to mount the spinning turbine in the spinning machine in such a manner that its rotary speed may be increased substantially and the yarn output correspondingly increased.

It is a particular object of the present invention to provide an improved bearing apparatus for spinning turbines, which reduces the effects of vibration and excessive speed so as to provide a smooth, more stable rotation.

These objects, others, and numerous advantages will be seen from the following disclosure.

SUMMARY OF THE INVENTION

According to the present invention apparatus for mounting the bearing assembly of a spinning turbine is provided comprising a bushing secured by its outer surface to the machine frame and having its inner surface radially spaced from the exterior of the bearing assembly. Interposed between the bushing and the bearing assembly is a resiliently yieldable member secured to at least a portion of the inner surface of the bushing and only to a portion of the outer surface of the bearing assembly to thereby mount the assembly to the bushing with a radial clearance about a substantial length thereof.

This arrangement has the advantage as compared to the known rigid mountings of making the bearing assembly capable of free vibration in the machine frame so that the stress forces on the bearing are substantially reduced permitting high rotational speeds. Correspondingly the noise caused during operation of the turbine is decreased providing quieter operation.

The invention is capable of various embodiments. In one advantageous embodiment a sleeve is coaxially arranged within the bushing to receive the housing assembly and the resiliently yieldable material is arranged between the sleeve and the bushing fixedly connecting these parts to each other.

Preferably, the bushing envelopes the bearing housing only over a portion of its length and specifically near one of its ends. The bearing housing may be thus deflected within the bushing in any desired radial direction. Forces which would thus be normally absorbed by either the frame or bearing assembly are thus absorbed by the resilient yieldable member contributing to a quiet, smooth operation of the turbine.

Rubber or synthetic elastomeric material similar to 10 rubber are used for the yieldable member which is preferably vulcanized or otherwise adhered over the entire circumference of the sleeve and to the outer circumference of the bushing.

According to a second design, the bushing consists of 15 two axially arranged parts which are connected movably with each other by means of the resiliently yieldable material, one of the parts being arranged in the machine frame and the other carrying the bearing assembly. In this form the resiliently yieldable member 20 is placed axially between the two parts.

Full and complete details of the present invention follow in the appended disclosure.

BRIEF DESCRIPTION OF THE DRAWINGS

FIG. 1 is vertical sectional view of a turbine bearing assembly and mounting apparatus according to the present invention, and

FIG. 2 is a view similar to that of FIG. 1 showing a 30 second form of the present invention.

DESCRIPTION OF INVENTION

The figures show only so much of the spinning machine frame and turbine or spinnerette as is necessary to understand the mounting of an individual turbine unit. The general features of a spinning machine, its construction and operation are well known, and it is therefore not believed necessary to fully describe the same here. Those skilled in this art are fully cognizant 40 of such machines and the literature is replete with information of them.

The embodiment of the present invention as seen in FIG. 1 comprises a hollow cylindrical bushing 10 provided with a similarly cylindrical sleeve portion 12 held substantially coaxially within it by a resiliently yieldable pad 16. The yieldable pad is made of rubber or similar material capable of vibration and is preferably vulcanized or otherwise secured to the inner surface 14 of the bushing 10 and the outer surface of the sleeve 12. The axial length of the sleeve, as clearly seen from the figure, corresponds only to a portion of the axial length of the bushing 10, extending from the rear end of the bushing inwardly toward the axial center thereof.

The resilient pad 16 extends from the inner edge of the sleeve 12 in contact with the inner surface 14 of the bushing 10 until it reaches the front end of the bushing 10. In this manner the resilient yieldable material covers the entire internal surface of the bushing 10. The thickness of the pad 16, however, tapers or decreases in radial dimension as it progresses from the end of sleeve 12 to the front end of the bushing 10 so that the wall thickness at the front end is less than half the wall thickness between the sleeve 12 and bushing 10.

Fixedly mounted within the sleeve 12 is a cylindrical bearing assembly 18 of conventional design comprising a cylindrical housing having a shaft 20, projecting from

each end, mounted therein by suitable ball or roller bearings. The shaft 20 has fixed to its forward end a spinnerette or turbine 22, and at its rear end a drive wheel or pulley 24 which is connected by conventional belt drive or other means to a source of rotary drive power. The bearing assembly, turbine, and pulley mechanisms are well known, as indicated earlier, and need not be further described.

Because of the cylindrical exterior of the bearing housing the tapering resilient pad 16 envelopes the exterior thereof without touching it, leaving a free annular space 26 or radial clearance between the bearing and the bushing 10.

The bearing is fixed only circumferentially at the portion to which it is secured to the sleeve 12. Lastly, the exterior surface of the bushing 10 is secured within a mounting hole formed in a support or frame member 28 of the machine in conventional manner.

Alternatively, the sleeve 12 may be omitted and the resiliently yieldable member 16 adhered or vulcanized directly to the surface portion of the bearing housing. The sleeve 12 functions to provide suitable sub-assembly formations for easy replacement. Similarly the tapering extension portion of the resiliently yieldable member may also be omitted and the annular clearance maintained free of the pad.

It will be apparent that the present concept is embodied in a mount having a bushing securable to the frame and an elastomeric resilient member interposed and secured to at least a portion of its inner surface and to substantially less than all of the entire surface of the bearing assembly.

The operation of the turbine of course conforms the conventional usage. That is, the pulley 24 connected to the source of power causes the shaft 20 to rotate the turbine 22 about its central axis. The faster the pulley 24 is driven the faster the turbine 22 is rotated.

It is evident from the above and reference to the drawing that the bearing assembly 18 is thus floatingly mounted within the frame. The resilient member 16 envelopingly secured to only a portion of the bearing housing permits the bearing assembly to move radially within the free annular space 26. The resiliently yieldable pad 16 secures the sleeve 12 to the bushing 10 while permitting relative vibration and movement between the sleeve and bushing. The tapering radial wall dimension of pad 16 permits a degree of angular deflection of the bearing housing free of contact with the bushing 10 or frame 28. The mounting arrangement thus illustrated enables the bearing assembly to vibrate freely so that any oscillatory stresses generated by the rotation of the turbine are not transmitted to the machine frame 28. Consequently, deleterious and harmful reactionary effects on the bearing drive shaft 20 are avoided. As a result the turbine can be run at significantly higher speeds than heretofore possible and at much lower noise levels.

In the embodiment seen in FIG. 2 the bearing assembly 30 (the turbine and pulley are not shown) is fixedly mounted within an annular sleeve member 32 which has a cylindrical inner surface and a wedge shape exterior surface. An outer bushing 34 is fixed to the frame 38 and also has a wedge shape surface corresponding to that of the interior bushing. The sleeve 32 and bushing 34 are substantially axially aligned. The

outer bearing has an inner cylindrical surface the radial dimension of which is greater than that of either the interior bushing 32 or the bearing housing 30, so that an annular space 40 is formed about the bearing housing 30. Permanently fixed, adhered, or vulcanized axially between the opposed slant or wedge surface of the inner bushing 32 and the outer bushing 34 is a yieldably resilient pad 38 of annular conical configuration. The pad 38 is of generally uniform thickness.

As seen in FIG. 2 this mounting arrangement is suitable for use where the thickness of the machine frame 36 is less than the axial length of the bearing housing 30. It is preferable that the outer bushing member 34 be at least substantially equal to the depth of the frame the inner portion to which the bearing housing 30 is fixed can thus extend beyond the frame 36. This arrangement is of course suitable for use in the form shown in FIG. 1 and has all the advantages described for it.

As seen in FIG. 2, the inner and outer bushings 32 and 34 respectively are provided with correspondingly opposed inclined or conical faces. This permits the insertion of an intermediate resilient pad of considerable length. As a result, the bearing housing 30 is permitted a large degree of vibratory movement and radial deflection without transmission of vibrations to the frame. The advantages and benefits of this second embodiment clearly parallel those obtained from the first.

It will thus be seen that the present invention provides apparatus for mounting turbine bearing assemblies in spinning machines capable of permitting the assembly to freely vibrate with transmission of the stresses and strains to the frame. Faster running turbines are thus permissible. Smoother, quieter operation is effected and above all increased yarn output is obtained.

Various modifications have been shown to the two embodiments. Numerous additional changes, modifications, and variations will suggest themselves to those skilled in this art. It is intended therefore that the present disclosure be taken as illustrative only of the present invention and not as limiting of its scope.

What is claimed:

1. Apparatus for securing to a machine frame an axially extending cylindrical bearing assembly having a central shaft carrying driven means mounted at one end and driving means at the other end comprising a cylindrical bushing having an outer surface secured to said machine frame and an inner surface radially spaced from the exterior surface of said bearing assembly, a resiliently yieldable member secured to at least a portion of the interior surface of said bushing and to the exterior surface of said bearing assembly, at one end thereof, to support said bearing assembly cantilevered within the bushing, said bushing spacedly enveloping the remainder of said bearing assembly and forming a radial clearance thereabout to permit radial deflection of said bearing assembly.

2. The apparatus according to claim 1 including a sleeve interposed between the resiliently yieldable member and the bearing assembly, said sleeve receiving and securely fixing said bearing assembly against movement.

3. The apparatus according to claim 2 wherein said sleeve extends axially over only a portion of said bear-

ing assembly extending from said one end toward the axial center thereof.

4. The apparatus according to claim 2 wherein said resiliently yieldable member is rubber and is vulcanized to said bushing and said sleeve.

5. The apparatus according to claim 2 wherein said bushing and said sleeve are co-axially arranged about said bearing sleeve, and said resiliently yieldable material is located co-axially therebetween.

6. The apparatus according to claim 5 wherein said bushing is axially longer than said sleeve and the inter-

mediate resiliently yieldable member extends along the interior surface of said bushing.

7. The apparatus according to claim 2 wherein said bushing and said sleeve are arranged substantially axially of each other and said yieldably resilient member is arranged axially therebetween.

8. The apparatus according to claim 7 wherein each of said bushing and sleeve are formed with opposed inclined faces between which a uniform resiliently

10 yieldable member is secured.
